UNITED STATES PATENT OFFICE.

GASTON METZGER, OF KANSAS CITY, MISSOURI.

SHOE-POLISHER.

982,287.

Specification of Letters Patent. Patented Jan. 24, 1911.

Application filed June 10, 1910. Serial No. 566,246.

To all whom it may concern:

Be it known that I, GASTON METZGER, a citizen of the United States, residing at Kansas City, in the county of Jackson and State 5 of Missouri, have invented certain new and useful Improvements in Shoe-Polishers, of which the following is a specification.

My invention relates to improvements in shoe polishers.

10 The object of my invention is to provide a shoe polishing apparatus, consisting of a brush, and a vessel carried thereby for containing polishing material, whereby the movement of the brush during the polishing 15 operation will keep the polishing material in the vessel thoroughly mixed and in condition for immediate use.

A further object of my invention is to provide a polishing apparatus in which the 20 vessel containing the polishing material may be stored in compact form within a hollow polishing brush and in which access to the polishing material contained in the vessel may readily be had.

25 Other novel features are hereinafter fully described and claimed.

In the accompanying drawings which illustrate the preferred form of my invention—Figure 1 is a perspective view of my 30 improved polishing brush. Fig. 2 is a central, vertical, longitudinal sectional view. Fig. 3 is a cross section on the dotted line *a—b* of Fig. 2. Fig. 4 is an enlarged, detailed, sectional view, taken on the dotted 35 line *c—d* of Fig. 1.

Similar characters of reference denote similar parts.

1 denotes the body of the polishing brush, said body consisting preferably of a 40 rectangular box having an opening in the top, and preferably provided with vertical, resilient sides, each having an inwardly extending, longitudinal depressed portion 2, which serves as a finger hold for enabling 45 the brush to be securely grasped, and serving also another purpose, which will be herein-after described.

The body 1 is provided preferably with 50 end openings 3, adapted to have inserted therethrough stoppers 4 for respectively closing the openings 5 in two horizontally disposed bottles 6, which are located in the hollow body 1, and serve as vessels for containing polishing material, which is preferably liquid. The vessels or bottles 6 are 55 horizontally disposed with the openings 5

in the necks respectively registering with the end openings 3. Between the bottles 6 the body 1 may be provided with a vertical transverse partition 7, which serves to prevent endwise movement of one of the bottles when the other is removed from the body 1.

To the bottom of the body 1 is secured a sheet 8 of polishing material, such as felt. 60 Covering the top opening of the body 1 is a cover 9, which is preferably detachable from the body. The cover may be releasably locked in the closed position by any suitable means. In the drawing I have shown each 65 end of the body provided with rounded, outwardly extending projections 10, which are adapted to spring into depressions 11, located on the inner sides of the downwardly extending end flanges 12 of the cover 9. 70 The cover 9 serves to prevent vertical movement of the bottles 6 and the inwardly extending portions 2 preferably clamp the sides of the bottles and prevent lateral movement thereof. The stoppers 4 may have secured to them the usual, inwardly extending rods 13, to the inner end of which are 75 respectively secured daubing brushes 14.

When the brush is used in the polishing 80 operation the rapid lengthwise movement 85 thereof will cause the polishing material contained in the bottles 6 to be thoroughly agitated and in proper position for instant use. When the daubing brushes are to be 90 used, the stoppers 4 may be extracted in the ordinary manner. When one of the bottles 95 6 has been emptied the stopper 4 thereof, together with its daubing brush, is removed through the adjacent end opening 3, after which the cover 9 is removed. The empty 100 bottle may then be taken from the body 1 through the top opening in the body and another bottle containing polishing material substituted therefor, the opening of the new bottle being closed after the bottle has been inserted, by inserting therein, through the adjacent end opening 3, a stopper 4.

Various modifications of my invention, within the scope of the appended claims, 105 may be made without departing from its spirit.

Having thus described my invention, what I claim and desire to secure by Letters Patent is:

1. A polishing brush having a hollow 110 body and an opening in the top for receiving a bottle or similar device, the side walls of

the body being resilient and having inwardly extending longitudinal depressions serving for finger grips and for gripping the bottle, and a cover for said opening and 5 serving as a support for the hand which operates the brush.

2. A polishing brush having a hollow body with an opening in the top for receiving a bottle, and having an end opening for 10 the insertion and removal of the cork of the bottle, the body having resilient side walls provided with inwardly extending depressions forming hand holds on the outside and projections on the inside of the body for 15 gripping the bottle.

3. A polishing brush having a hollow body with an opening in the top for receiving a bottle, and having resilient side walls provided with inwardly extending depressions forming hand holds on the outside and 20 projections on the inside of the body for gripping the bottle.

In testimony whereof I have signed my name to this specification in presence of two subscribing witnesses.

GASTON METZGER.
